UNITED STATES PATENT OFFICE

91,545

DESIGN FOR A RADIOCABINET OR THE LIKE

Miller Stansbury, Washington, D. C.

Application November 9, 1933. Serial No. 49,684

Term of patent 14 years

To all whom it may concern:

Be it known that I, MILLER STANSBURY, a citizen of the United States, residing at Washington, in the District of Columbia, have invented a new, original, and ornamental Design for Radiocabinets or the like, of which the following is a specification, reference being had to the accompanying drawing, forming part thereof.

Figure 1 is a perspective view of a radiocabinet or the like, showing my new design.

Figure 2 is an enlarged cross section of the

wheel element, taken at a point other than through the spokes, showing the recessed or indented central portion of the hub.

The side of the cabinet not shown is understood to bear the same ornamental design as the side shown.

I claim:

The ornamental design for a radiocabinet or the like, as shown and described.

MILLER STANSBURY.
